UNITED STATES PATENT OFFICE.

CHARLES N. TUCKER, OF GREAT FALLS, ASSIGNOR TO HIMSELF AND FREDERICK DEMARS, OF SOMERSWORTH, NEW HAMPSHIRE.

LOOM-SHUTTLE.

SPECIFICATION forming part of Letters Patent No. 251,973, dated January 3, 1882.

Application filed May 31, 1881. (No model.)

To all whom it may concern:

Be it known that I, CHARLES N. TUCKER, of Great Falls, of the county of Strafford and State of New Hampshire, have invented a new and useful Improvement in Loom-Shuttles; and I do hereby declare the same to be described in the following specification and represented in the accompanying drawings, of which—

10. Figure 1 is a top view, Fig. 2 a longitudinal section, and Fig. 3 a transverse section, of a shuttle provided with my invention, the nature of which is defined by the claims herein-after presented. Fig. 4 is a horizontal and 15 longitudinal section of the spindle and its expander.

The improvement relates to mechanism for expanding the shuttle-spindle in order to enable it to firmly hold the cop while the spindle 20 may be in use.

In the drawings, A denotes the body of the shuttle; B, the spindle, and C the operative-spring of the latter, arranged and applied in the ordinary way, the spindle being an expansive one—that is to say, it is split lengthwise from near its toe or point to or through its heel, and has within it an expander, D, which is tapering or wedge-shaped, as shown. This expander, on being drawn back within the spindle, 25 expands it laterally, the spindle on the expander being forced forward within it, contracting by its inherent elasticity. This expander, at its rear part, is bent at a right angle and extends upward through a slot, a, 30 in the spindle, and is jointed to the wrist of a link or double crank, E, such crank being arranged in the body of the shuttle and pivoted thereto or to a metallic carrier, F, inserted in the said body and formed as represented. 35 The link or double crank straddles the front portion, b, of the spring C in manner as shown in the drawings, so as to leave the spring free to bear and act on the heel or head c of the spindle, the shuttle-body being suitably re-

cessed to admit of the necessary vertical play 45 of the link or double crank within it. On raising the spindle in the shuttle-body the expander will be forced forward within the spindle, which in the meantime will contract laterally; but on the spindle being provided with 50 a cop and moved down into the chamber of the shuttle-body the expander, during the downward movement of the spindle and cop, will be drawn backward within the spindle and will expand the latter so as to cause it to hold the 55 cop firmly upon it.

I would observe that I am aware that it is not new to provide a shuttle-spindle with mechanism for expanding it relatively to a cop placed on it while the spindle may be in the 60 act of being turned down into the shuttle-body, and therefore I make no claim to such in the abstract; nor do I claim the expander hooked at its rear part and over a stationary pin and kept thereon by a spring, all as shown in the 65 British Patent No. 1,099 for 1854.

What I claim as my improvement is as follows, viz:

1. The link or double crank E, arranged and combined substantially as set forth, with the 70 shuttle-body, the expander, and the split or expansive spindle, all being essentially and to operate as specified.

2. The link or double crank and its pivotal carrier inserted in the shuttle-body, in combination therewith and with the expansive spindle and its expander, all being adapted substantially as set forth. 75

3. The link or double crank, in combination and arranged with the shuttle-body, the expansive spindle, and its expander and operative spring, substantially in manner as shown and described. 80

CHARLES N. TUCKER.
